UNITED STATES PATENT OFFICE.

ALFRED WILLIAMS, OF SEATTLE, WASHINGTON, ASSIGNOR OF ONE-HALF TO
THOMAS W. GORDON, OF SAME PLACE.

FILTER.

SPECIFICATION forming part of Letters Patent No. 499,815, dated June 20, 1893.

Application filed November 9, 1891. Renewed May 8, 1893. Serial No. 473,484. (No model.)

To all whom it may concern:

Be it known that I, ALFRED WILLIAMS, a citizen of the United States, residing at Seattle, in the county of King and State of Washington, have invented a new and useful Filter, of which the following is a specification.

The invention relates to improvements in filters.

The object of the present invention is to simplify and improve the construction of filters, and to provide one which will remove all organic matter in suspension, and which will destroy all animal life, microbes, and the like, and which will remove free ammonia and nitrous acids, from water passing through it.

The invention consists in the construction and novel combination and arrangement of parts hereinafter fully described, illustrated in the accompanying drawings and pointed out in the claim hereto appended.

In the drawings—Figure 1 is a side elevation of a filter constructed in accordance with this invention. Fig. 2 is a central longitudinal sectional view.

Like numerals of reference indicate like parts in both figures of the drawings.

1 designates a filter casing provided with an inner chamber 2 adapted to contain particles or globules of iron, and which is divided 30 by a curved diaphragm 3 extending to within a short distance of the bottom of the casing, and formed integral with the latter. The upper end of the casing 1 is exteriorly threaded and has attached to it an interiorly threaded coupling 4 adapted for the reception of the outer end 5 of a faucet which is secured therein by clamping screws 6 arranged in threaded openings of the coupling 4, and engaging the end 5 of the faucet. The top of the faucet 40 around the opening 7 forms a seat 8 for a strainer 9 which is very fine and a rubber gasket 10 against which the end of the faucet 5 bears. The outer side of the casing is provided with an interiorly threaded opening 11 in which is screwed the inner end 12 of a nozzle 13, and the outer end of the latter is provided with a strainer 14.

The water entering passes through a very

fine strainer into the chamber 2 of the filter, and is caused by the curved diaphragm to 50 pass downward between the same and the inner side of the casing, and then upward between the diaphragm and the outer side of the casing to the inner end of the nozzle, thereby bringing the water into contact with 55 all the particles or globules of iron, which are maintained in a state of frictional motion when the water is running. All free ammonia, so frequently found in impure water and all foreign matter either in solution or 60 gas assimilates with the iron and their effect is destroyed. It has been found by experience that water under a pressure from ten to one hundred and thirty pounds to the square inch in passing through the filter contacts 65 sufficiently with the iron to neutralize the effects of poisonous gases or solutions or any bad effect of the animal or organic matter caught in the strainers.

The coupling has its upper end interiorly 70 threaded and is adapted for the reception of an exteriorly threaded nozzle or a smooth faucet.

What I claim is—

In a filter, the combination of a casing having a chamber for containing a filtering material and provided with a depending curved diaphragm formed integral with it and arranged within the chamber and extending from the top thereof to within a short distance of the bottom, said casing having its 75 upper end exteriorly threaded and forming a seat and provided at its front with an interiorly threaded nozzle opening, a coupling provided with set screws and screwing on the upper threaded end of the casing, a strainer 80 arranged within the coupling on the seat, and a nozzle extending from the nozzle opening and provided at its outer end with a strainer, 85 substantially as described.

In testimony that I claim the foregoing as 90 my own I have hereto affixed my signature in the presence of two witnesses.

ALFRED WILLIAMS.
